UNITED STATES PATENT OFFICE.

JOSEPH T. WENSIULIS, OF NEW YORK, N. Y., ASSIGNOR TO COLUMBIA MACHINE WORKS & MALLEABLE IRON CO., OF BROOKLYN, NEW YORK, A CORPORATION OF NEW YORK.

OIL-BURNER.

1,398,709.

Specification of Letters Patent. Patented Nov. 29, 1921.

Application filed January 9, 1920. Serial No. 350,294.

To all whom it may concern:

Be it known that I, JOSEPH T. WENSIULIS, a citizen of Russia, residing in the borough of Queens, county of Queens, city and State 5 of New York, have invented an Improvement in Oil-Burners, of which the following is a specification.

My present invention is one that relates to an apparatus for burning fuel oil for the 10 particular purpose of heating blast furnaces, although obviously it is not limited to this particular use, the object of the invention being to so construct an oil burner for this and similar uses that the oil and air are adequately mixed and discharged in such a 15 manner to the furnace or other place to be heated that the resultant combustion is substantially complete.

In carrying out the invention, I prefer- 20 ably employ a nozzle having an oil discharge passage and fitted with a cap providing for a substantially concentric air discharge passage and a device operated by the discharge of the air and oil for mixing and distribut- 25 ing the same in such a manner, as hereinbefore stated, that the resultant combustion of the oil is as complete and perfect as possible, whereby the deposits accumulating on the furnace or other chambers heated by oil 30 burners is eliminated, making the cleaning of the furnace unnecessary, as well as reducing the number of burners necessary to establish and maintain a predetermined heat because of the increased efficiency of the 35 burner by producing substantially complete or perfect combustion. Experience has demonstrated the fact that in the use of the burner with a blast furnace, for example, one burner made in accordance with my invention 40 answers the purpose of a double burner or two burners which were heretofore employed for accomplishing the same work.

The oil burner made in accordance with my present invention will be hereinafter 45 more particularly described in conjunction with the accompanying drawings in which,—

Figure 1. is a central longitudinal cross section of an oil burner made in accordance with this invention.

Fig. 2 is a plan view of the nozzle member.

Fig. 3 is a plan of the cap member associated with the nozzle member.

Fig. 4 is a side elevation of one form of revoluble ejector member.

Fig. 5 is an end view of the same,

Fig. 6 is a side elevation of another form of revoluble ejector.

Fig. 7 is a more or less diagrammatic plan of a blast furnace illustrating the use of the burner in connection therewith, and 60

Fig. 8 is an elevation and partial cross section on line 8—8, Fig. 7.

Referring to the drawing, the oil burner made in accordance with my invention preferably comprises a nozzle member 10 made 65 with an offset portion 11, there being a longitudinal bore 12 in the nozzle member and a similar bore 13 in the offset portion, which bores communicate with one another at right angles, as clearly shown in Fig. 1 of the 70 drawing. The nozzle member 10 is provided with a reduced part 15, the surface of which is screw threaded, and with a still further reduced end 16. The nozzle also includes a cap 17 adapted to fit over and be turned 75 down to place on the screw threaded reduced portion 15 of the body of the nozzle 10, and the cap 17 is also provided with an offset portion 18 corresponding with the offset portion 11. The bore in the cap 17 is of such a 80 diameter as to provide an annular discharge space 19 between the same and the outer surface of the reduced end portion of the nozzle, while the offset portion 18 is provided with a bore 20 communicating with the annular 85 discharge passage or space 19. Within the longitudinal bore of the nozzle member, I employ a rod 21. In a predetermined position, this is fitted with a sleeve 22 having a screw threaded surface so as to be turned 90 down into the tapped opening 14 provided therefor in the left hand end of the nozzle member, as seen in Fig. 1, to secure the rod in position longitudinally in the nozzle member, and this rod 21, in suitable positions, is 95 also provided with lugs 23 adapted to engage with the surface of the bore in the reduced end of the nozzle member so as to maintain the rod in its proper axial position in the nozzle member. As will be understood, 100 when the rod 21 is in position in the bore of the nozzle member, it provides an annular discharge passage 24 between the same and the surface of the bore within the nozzle member and the reduced end thereof.

The apparatus hereinbefore described is preferably placed within an elbow or other part of an air duct or pipe leading to the tuyers in a blast furnace or other opening leading to any chamber which it is desired 110

to heat by the burner. As illustrated in the drawing, the part of the duct in which the burner is placed has an elbow 25. The burner is secured in position in the elbow 5 by the pipe lines through which the oil and air are supplied respectively to the annular discharge passages 24 and 19, the former of which is indicated at 26 and passes through an opening provided therefor in the duct 25 10 and is turned down into the end of the offset portion 11 of the nozzle member and is secured in position by a nut 27 or otherwise, this pipe line being employed to convey the oil to the burner. The other pipe line is indicated at 28 and similarly passes through an opening provided therefor in the elbow 25 of the air duct and is turned down into the end of the offset portion 18 of the cap member 17, being secured in position by a 15 nut 29 or otherwise. In the pipe line 26, there is a valve 30 to regulate and control the passage of the oil, and in the pipe line 28, there is a valve 31 to regulate and control the passage of the air. Oil passing through 20 the pipe line 26, as will be understood, is conveyed to the annular discharge passage 24, while the air flowing through the pipe line 28 is conveyed to the annular discharge passage 19 between the cap member 17 and 25 the reduced end of the nozzle member. Further, as indicated, the discharge orifices of these passages, that is the annular passage 24 and the annular passage 29, are substantially coincident at the right hand end 30 of the nozzle, as viewed in Fig. 1, and the orifice of the discharge passage 19 for the air is preferably curved inwardly so as to direct the same into the path of the oil as discharged from the orifice of the passage 24 35 and also into the ejector and distributing device hereinafter described. In the form of the apparatus, as hereinbefore described, the pipe line connections are both made through the bottom or inside of the air duct elbow 40 25, but as will be understood either one or both of these pipes may be supplied from the upper side or from either of the other sides of the elbow and for this purpose as illustrated in Fig. 1, I have provided the upper side of the elbow, for example, with openings which, as illustrated, are closed by the plugs 29'. 45

As illustrated in the drawing, the rod 21 is made sufficiently long to be carried through 50 a gland 32 set in an offset portion 33 of the air duct elbow 25, and at this extremity of the rod, the same is provided with a square portion 34 by means of which the same may be unscrewed from the nozzle 55 member and by the removal of the gland, the entire rod may be taken out of the nozzle after the distributing device, as herein-after described, has also been removed for the purpose, for example, of cleaning the 60 bore of the nozzle or obviously for replac- 65

ing another rod should this become necessary. At the opposite end of this rod 21 or that end thereof adjacent the discharge orifice of the nozzle member, the rod is of reduced cross section and the reduced end 70 thereof, as indicated at 35, forms a bearing for an ejector distributor member 36 which is journaled thereon, being adapted to turn on this reduced end 35 as its axis. The ejector distributor member 36 is preferably conical and as indicated in Figs. 4 and 5, may be provided with longitudinal or straight ribs and intervening grooves 37, or as indicated in Fig. 6 may be provided with series of spiral ribs and corresponding intermediate spiral grooves 38, this latter being the preferable form of ejector distributor. In either event, the ejector distributor is maintained in position on the reduced end of the rod as its axis by means of a washer 39 80 and a lock nut 40.

In the use of the apparatus, the burner is set, for example, when employed with a blast furnace in substantially the position as shown in Figs. 7 and 8 of the drawing. 90 The elbow of the air duct as illustrated may be fitted with a damper 41 to control the passage of the air therethrough and the discharge end of the air duct is placed at or adjacent the orifice of the twyer 45 in the 95 body 42 of the blast furnace, which, as illustrated is provided with a frame 44 supported upon a suitable base 43. Furthermore in the use of the apparatus, suitable quantities of oil and air are applied to the nozzle member and ejected therefrom, and an additional quantity of air may be supplied through the air duct, being discharged from the orifice of the elbow 25 thereof and, as will now be understood, in the use of the apparatus the 100 oil and air being discharged from the orifices of the annular passages in the nozzle cause the ejector distributor to revolve, which, in so doing, not only mixes the air and oil thoroughly, but distributes and ejects 110 the same in such a manner that combustion of the oil is practically complete.

I claim as my invention:

1. In an oil burner and in combination, a nozzle having a discharge passage for oil, 115 a discharge passage for air substantially concentric with the discharge passage for the oil, the said passages terminating in orifices lying in substantially the same plane, and a revoluble distributor member having one end 120 thereof lying in substantially the same plane as the orifices of the said passages so as to be operated by the discharge of the oil and air.

2. In an oil burner and in combination, a 125 nozzle member having a longitudinal bore therethrough, a rod in the bore of the nozzle member providing therein an annular oil discharge passage, a member secured to the said nozzle and providing therein an an- 130

- nular air discharge passage, the air passage being curved inwardly adjacent its orifice to cause the same to lie in substantially the same plane as the orifice of the oil passage, 5 the said discharge passages having substantially coincident discharge orifices, and a distributor member journaled on the rod adjacent the discharge orifices of the said oil and air passages and adapted to be operated 10 by the discharge of the oil and air therefrom.
3. In an oil burner and in combination, a nozzle member having a longitudinal bore therethrough, a rod in the bore of the nozzle member providing therein an annular oil discharge passage, means for securing and centering the said rod in the bore of the said nozzle member, a member secured to the said nozzle and providing therein an annular 20 air discharge passage, the air passage being curved inwardly adjacent its orifice to cause the same to lie in substantially the same plane as the orifice of the oil passage, and a distributor member journaled on the rod 25 adjacent the discharge orifices of the said oil and air passages and adapted to be operated by the discharge of the oil and air therefrom.
4. In an oil burner and in combination, a nozzle member having a cylindrical portion of reduced cross section and a longitudinal bore therein, a rod extending through the bore in the nozzle member to provide an annular passage therein, a cap adapted to 30 fit over the reduced end of the said nozzle member to provide therein an annular passage substantially concentric with the aforesaid annular passage, the air passage being curved inwardly adjacent its orifice to cause 35 the same to lie in substantially the same plane as the orifice of the oil passage, means for supplying a liquid fuel to the annular passage between the said rod and the surface of the bore in the nozzle member, means for 40 supplying air to the annular passage between the said cap and the reduced end of the nozzle member, and a revoluble distributor member journaled on the end of the 45 said rod adjacent the discharge orifices of the said annular passages and operated by the discharge of the liquid fuel and air therefrom.
5. In an oil burner and in combination, a nozzle having a longitudinal bore therein, a rod extending through the bore of the nozzle and providing therein an annular passage, means for securing and centering the said rod in the bore of the nozzle, an offset member extending from the nozzle and provided 55 with a passage communicating with the said annular passage, a cap secured to the said nozzle and extending over a reduced portion thereof to provide an annular passage between the said reduced portion of the nozzle 60 and the said cap, an offset extending from 65
- the said cap and having a passage therein communicating with the said annular passage between the cap and the reduced portion of the nozzle, a pipe line connected to the offset extending from the cap member for 70 conveying air under pressure to the annular passage between the cap and the reduced end of the nozzle, and a revoluble distributor member journaled on the end of the said rod adjacent the discharge orifices of the 75 said passages and operated by the discharge of the fuel oil and air therefrom.
6. In an oil burner and in combination, an air duct member, a nozzle within the air duct member and having a longitudinal bore 80 therein, a rod extending through the bore of the nozzle, means for securing and positioning the rod in the bore of the nozzle to provide an annular discharge passage 85 therein between the said rod and the surface of the bore, a cap secured to a reduced end of the said nozzle and providing between the same and the cap an annular discharge passage substantially concentric with the aforesaid discharge passage, the said discharge 90 passages having substantially coincident discharge orifices, means secured in the said air duct member and through which the said rod passes so as to make the rod removable from the nozzle and the air duct member, 95 means for supplying fuel oil and air to the said annular passages, and a revoluble distributor member journaled on the end of the said rod adjacent the discharge orifices of the 100 said passages and operated by the discharge of the oil and air therefrom.
7. In an oil burner and in combination, an air duct member, a nozzle within the air duct member and having a longitudinal bore therein, a rod extending through the bore of the nozzle, means for securing and positioning the rod in the bore of the nozzle to provide an annular discharge passage 105 therein between the said rod and the surface of the bore, a cap secured to a reduced end of the said nozzle and provided between the same and the cap an annular discharge passage substantially concentric with the aforesaid discharge passage, the said discharge 110 passages having substantially coincident discharge orifices, means secured in the said air duct member and through which the said rod passes so as to make the rod removable from the nozzle and the air duct member, an offset 115 extending from the said nozzle and being provided with a passage communicating with the annular passage between the rod and the surface of the bore of the nozzle, a fuel pipe extending through the said air duct member and into the said offset for supplying fuel 120 oil to the annular passage between the rod and the surface of the bore of the nozzle, an offset extending from the said cap, a pipe line extending through the said air duct member and into the offset extending from 125 130

the cap in which there is a passage communicating with the annular passage between the cap and the reduced end of the nozzle whereby air under pressure is supplied to the last 5 aforesaid annular passage, and a revoluble distributor member journaled on the end of the said rod adjacent the discharge orifices of the nozzle and actuated by the discharge of the fuel oil and air therefrom.

10 8. In an oil burner and in combination, an air duct member, a nozzle within the air duct member and having a longitudinal bore therein, a rod extending through the bore of the nozzle, the said rod having a portion extending beyond the orifice of the said discharge passage and of reduced cross section adapted to form a bearing, means for securing and positioning the rod in the bore of the nozzle to provide an annular discharge 15 passage therein between the said rod and the surface of the bore, a cap secured to a reduced end of the said nozzle and providing between the same and the cap an annular discharge passage substantially concentric with the aforesaid discharge passage, the said discharge passages having substantially co-incident discharge orifices, means secured in the said air duct member and through which the said rod passes so as to make the rod re-

movable from the nozzle and the air duct 30 member, an offset extending from the said nozzle and being provided with a passage communicating with the annular passage between the rod and the surface of the bore of the nozzle, a fuel pipe extending through the 35 said air duct member and into the said offset for supplying fuel oil to the annular passage between the rod and the surface of the bore of the nozzle, an offset extending from the said cap, a pipe line extending through the said air duct member and into the offset extending from the cap in which there is a passage communicating with the annular passage between the cap and the reduced end of the nozzle whereby air under 40 pressure is supplied to the last aforesaid annular passage, a conical distributor member journaled on the bearing provided therefor at the reduced end of the said rod adjacent the orifices of the discharge passages, the 45 said distributor member having series of spiral ribs and intervening recesses, and means for securing the said distributor member in position on its bearing.

Signed by me this 22 day of December, 55
1919.

JOSEPH T. WENSIULIS.
